UNITED STATES PATENT OFFICE.

GEORG WOLFF, OF HERMSDORF, NEAR BERLIN, GERMANY, ASSIGNOR TO BERGMANN-ELEKTRICITÄTS-WERKE, AKTIENGESELLSCHAFT, OF HERMSDORF, NEAR BERLIN, GERMANY, A CORPORATION.

CURRENT-DISTRIBUTING NETWORK.

1,098,204.

Specification of Letters Patent. Patented May 26, 1914.

Application filed October 1, 1912. Serial No. 723,374.

To all whom it may concern:

Be it known that I, GEORG WOLFF, subject of the German Emperor, and residing at Hermsdorf, near Berlin, Germany, have invented certain new and useful Improvements in Current-Distributing Network, of which the following is a specification.

My invention relates to a current distributing network, consisting of main conductors, auxiliary conductors and devices to separate the main conductors automatically in sections from one another, as soon as a fault in the insulation occurs.

The desired object is attained by arrangements, consisting of several separate main conductor sections, running parallel to these, also separate, auxiliary conductor sections insulated from the earth, switches for connecting the main conductor sections at their ends, and means by which the switches at both ends of the corresponding main conductor section are automatically opened as soon as through a fault in the insulation the neutral point is displaced in relation to the auxiliary conductor section.

In the drawings herewith, Figure 1 is a diagrammatic cross section through a three-core three phase cable such as may be employed in my invention; Figs. 2 and 3 are cross sections of slightly different forms of cable; Fig. 4 is a diagram showing how the cores of such cable may be connected to the auxiliary conductor; Fig. 5 shows a vertical section and a plan view of the potential relay employed; and Figs. 6, 7 and 8 are diagrams of slight modifications as hereinafter explained.

The appended Figs. 1 to 5 explain the invention for instance in reference to a high tension, three-core, three phase cable. The cross section through the cable in Fig. 1 shows the three main cores a_1 , a_2 and a_3 , which with insulating material in between are surrounded by sheaths h , constituting the auxiliary conductor, these sheaths being electrically interconnected. As long as the cable is intact the auxiliary conductor h then forms the neutral point of a three phase system and three voltmeters v_1 , v_2 , and v_3 , connected between it and the three cores a_1 , a_2 , a_3 , direct or through a three phase potential transformer, will show the same readings. If, however, a fault develops in the cable the symmetry of the system will

be at once destroyed and the readings of the 55 voltmeters will differ.

The form of auxiliary conductor shown in Fig. 1 can be made by pressing a metal sheath around the cores, or by lapping them with metal tape, or in some similar manner, 60 but this method does not affect the main idea of the invention. Thus, for instance, Fig. 2 shows an auxiliary conductor which is split up into a number of single parallel wires d placed around and in between the 65 main conductors, and Fig. 3 shows cores a_1 , a_2 and a_3 inclosed in a sheath m and a central conductor n which form either individually or combined the auxiliary conductor, but these examples do not exhaust, in 70 any way, the different methods of forming the auxiliary conductor.

As shown in Fig. 4 at both ends of the section of three phase cable, the three main cores a_1 , a_2 , a_3 are connected to the auxiliary 75 conductor h through the primary windings of potential transformers t_1 , and t_2 , to the secondary windings of which the three phase potential relays r_1 and r_2 are connected. As long as the cable section is intact and the 80 auxiliary conductor forms the neutral point of the three phase system, the three forces working on each relay are equal and in perfect equilibrium. This equilibrium, however is upset as soon as through a short circuit or a fault to earth in the cable, the auxiliary conductor loses its property as the neutral point, and the consequence is that the contacts k_1 and k_2 of the relays close, whereby the current of the auxiliary batteries b_1 and b_2 or current from any other source acts on the release coils s_1 and s_2 and trips the latches 1, 1₂ of the switches o_1 and o_2 and thereby opens the latter.

Fig. 6 shows a section of direct current 95 cable, consisting of two single cores a_1 and a_2 surrounded by sheaths h_1 and h_2 which constitute the auxiliary conductors and these latter again are electrically interconnected at the ends of the cable and further 100 connected with the neutral points of the respective potential relays v_1 and v_2 . The forces of both coils of each relay neutralize one another as long as the cables are intact, but, on the other hand, on a fault developing in one cable the torque of one relay coil will exceed that of the other and contact 105 will then be made at k_1 and k_2 with the

effect that in the same way as described in Fig. 4 the cable sections are then disconnected by switches o_1 and o_2 . These safety devices are also suitable for overhead networks for disconnecting any section, should the insulators break down, the auxiliary conductor being connected electrically with the insulator supports. In this case, in order that this arrangement may work correctly, the essential insulation of the auxiliary conductor from ground may be obtained by insulating the insulator supports from the poles, unless wooden poles be used and the insulating quality of the wood be sufficient for this purpose.

Fig. 5 shows diagrammatically the construction of a three-pole potential relay, such as would be used for protecting a three phase line. A three-armed armature e is arranged above the phase coils c_1 , c_2 , c_3 which is held in equilibrium when the torque of the coils is equal, but which is tilted as soon as the power of one or two coils exceeds that of the other or others, thus closing one of the auxiliary contacts i and thereby causing the switch to open. Should a short circuit take place simultaneously between all three phases, it could, however, happen that the potential differences between all three phases and the auxiliary conductor may sink to zero and the relay coils would then exert no power on the armature at all and in spite of the fault in the cable no contact would be made at i . In order to prevent this, the relay can be provided with a spring f which presses the three-armed armature against contacts i , thereby closing them as soon as the torque of the coils completely disappears. As, however, the spring f would also act and close the contacts i , should, at times, the voltage in the power station disappear, and as in such a case the disconnection of any cable sections would not be desirable, the closing of the auxiliary circuit for the automatic release can be made dependent upon the presence of a current in the main conductor, either by using as a source of current for the releasing current the secondary windings of current transformiers in the main conductor, or by opening the releasing current circuit by means of current relays influenced by the current in the main conductors, as soon as the current disappears in the main conductors through the voltage in the central station failing.

The first of these devices illustrated in Fig. 7 shows current transformers W_1 , W_2 , and W_3 connected in the main conductors, the secondaries of these current transformiers being connected with a release coil S so that when contact points k are closed the coils will not be energized unless current is flowing in the main conductors. The second device above referred to is shown in Fig. 8, where the solenoids m_1 , m_2 and m_3

are connected in series with the main conductors, these solenoids normally holding the armatures in an elevated position, so to close the circuit through releasing coil and a local battery b . When current flowing in at least one of the main conductors it is obvious that the circuit through the magnet S will be complete.

What I claim is:—

1. A cable made in sections, each comprising a plurality of main cores and an auxiliary conductor constituting the neutral point of the section; combined with main coils respectively connected with said cores and connected with said auxiliary conductor, secondary coils respectively parallel with said main coils, and instrumentalities severally connected with said secondary coils.

2. A cable made in sections, each comprising a plurality of main cores and a plurality of wires interconnected at the ends of the section and constituting an auxiliary conductor, the latter constituting the neutral point of the section; combined with main coils respectively connected at one end with said cores and all connected at their other ends with said auxiliary conductor, secondary coils respectively parallel with said main coils, and instrumentalities severally connected with said secondary coils.

3. A cable made in sections, each comprising a plurality of main cores and a plurality of wires interconnected at the ends of the section and constituting an auxiliary conductor, the latter constituting the neutral point of the section; combined with main coils respectively connected at one end with said cores and all connected at their other ends with said auxiliary conductor, secondary coils respectively parallel with said main coils, switches between the sections, an switch-opening mechanism actuated by current generated in any secondary coil.

4. A cable made in sections, each comprising a plurality of main cores and an auxiliary conductor constituting the neutral point of the section; combined with main coils respectively connected with said cores and connected with said auxiliary conductor, secondary coils respectively parallel with said main coils, switches between the sections, devices for opening each switch, electrically operated mechanism for actuating said devices, a circuit closer in the circuit of such mechanism, and means for closing the circuit closer by a current generated in an secondary coil.

5. A cable made in sections, each comprising a plurality of main cores and an auxiliary conductor constituting the neutral point of the section; combined with main coils respectively connected with said cores and all connected with said auxiliary conductor, secondary coils respectively parallel with said main coils, switches between the sec

tions, a latch for opening each switch, a coil for actuating the latch, a motive circuit for this coil, and a circuit closer in such circuit actuated by a current generated in any secondary coil.

6. A cable made in sections, each comprising a plurality of main cores and an auxiliary conductor constituting the neutral point of the section; combined with main coils respectively connected with said cores and all connected with said auxiliary conductor, secondary coils respectively parallel with said main coils, switches between sections, a latch for each switch, a relay circuit having a coil for actuating said latch, an open relay circuit, and means for closing it by a current generated in any secondary coil.

7. A cable made in sections, each comprising a plurality of main cores and an auxiliary conductor constituting the neutral point of the section; combined with a potential transformer whose primary coils are connected with the main cores respectively and with said neutral point, potential relays connected with the secondary coils of said transformer, a switch connecting each two cable sections, and means for opening the same by the closing of the contacts in any relay.

8. A three core, three phase cable made in sections, an auxiliary conductor extending

along each section, and a three-part switch connecting the respective cores between contiguous sections; combined with a potential transformer whose primary windings are connected respectively to the cores and collectively to the auxiliary conductor, three-phase potential relays connected with the secondary windings of said transformer, and means for opening the switch by the closing of the contacts in any relay.

9. A three core, three phase cable made in sections, an auxiliary conductor extending along each section, and a three-part switch connecting the respective cores between contiguous sections; combined with a potential transformer whose primary windings are connected respectively to the cores and collectively to the auxiliary conductor, three-phase potential relays whose coils are connected with the secondary windings of said transformer, a three-armed armature whose arms overlie said coils respectively, a relay circuit closed by the rise of any arm, and means actuated by the coils of the relay circuit for opening said switch.

In testimony whereof I affix my signature in presence of two witnesses.
